UNITED STATES PATENT OFFICE.

FRANK H. MARKER, OF ELKHART, INDIANA, ASSIGNOR, BY DIRECT AND MESNE ASSIGNMENTS, OF TWO-THIRDS TO ELLIS M. CHESTER, OF SAME PLACE, AND CARLTON E. SAGE, OF ELKHART COUNTY, INDIANA.

LAMP TRIMMING AND EXTINGUISHING APPARATUS.

SPECIFICATION forming part of Letters Patent No. 349,599, dated September 21, 1886.

Application filed October 27, 1885. Serial No. 181,092. (No model.)

To all whom it may concern:

Be it known that I, FRANK H. MARKER, a citizen of the United States, residing at Elkhart, in the county of Elkhart and State of Indiana, have invented a new and useful Improvement in Lamp Trimming and Extinguishing Attachments, of which the following is a specification, reference being had to the accompanying drawings.

10 This invention relates to lamp-burners; and it has for its object to provide an attachment for the same, which will serve to extinguish the light and trim the wick at the same time.

The design of the present invention resides, 15 more particularly, in certain improvements on the construction shown in Letters Patent No. 321,989, granted to me July 14, 1885.

20 The invention consists in certain details of construction and novel combination of parts, as will be hereinafter set forth, and particularly specified in the claims.

In the accompanying drawings, Figure 1 is 25 a perspective view of a lamp-burner with my improvement applied thereto, the hinged cap of the burner being thrown back to expose the wick-tube and the proximate parts. Fig. 2 is a transverse vertical section through the wick-tube with the cap closed down, the attachment being shown in dotted lines in the 30 position assumed when extinguishing the light and trimming the wick. Fig. 3 is a detail perspective view of my attachment detached from the wick-tube. Fig. 4 is an elevation of the front side of my attachment. Fig. 5 is a 35 detail perspective view of the operating-rod, showing the blade held rigidly by rivets to the same.

40 Like letters are used to indicate corresponding parts in the several figures.

Referring to the drawings, A designates a lamp-burner of the ordinary construction, a description of which would appear to be unnecessary for a full understanding of the present improvement.

45 In applying my attachment, a plate, B, is secured by solder or otherwise over A', the perforated diaphragm of the burner, on one side of the wick-tube C, and is provided with curved arms D on each side, which extend 50 upward and are soldered to the opposite up-

per ends of the wick-tube. Eyes a' are provided on the plate B at its inner edge, adjacent to the wick-tube.

E designates a wire rod having the main longitudinal arm a' journaled in the eyes a' of 55 the plate B, the inclined arm b, at the outer end of the arm a, passing through a slot, c, of the diaphragm A, and having its lower end turned outward, as at e, to provide an operating-handle. At the inner end of the main 60 arm a the wire rod is bent outward and slightly upward a short distance, as at d, in a direction at right angles to the main arm, and then longitudinally, as at f, to provide a pintle on 65 which the extinguishing and trimming blade is pivoted. Said blade F is shaped substantially like a hoe-blade in cross-section, its lower or front edge being sharpened. The rear or upper edge is provided with eyes g, through which the arm f of the rod E is 70 passed. Between the eyes the blade is cut out and pressed upward, as at h, to form an extension, for the purpose presently described. A spring, G, is coiled on the main arm a, between the eyes a' of the plate B, one end of 75 the spring being secured to the plate and the other end extending outward or upward until it reaches the arm f, around which it is coiled between the eyes g of the blade F, the other end of the spring being secured to 80 the extension h. By this arrangement of the spring G it is caused to press the extension h upward and force the blade downward onto the upper edge of the wick-tube; and it also imparts a spring action to the wire 85 rod E, so as to retain the parts normally out of engagement with the wick-tube. The blade F is set at an incline, its outer sharpened edge being lower than the point of connection with the operating-rod on its pivotal point, and in 90 this manner the sharpened edge only of the blade acts upon the upper edge of the wick-tube. The curved arms D serve to guide the blade in its movements, the spring G retaining the sharpened edge of the blade normally 95 in engagement with the upper edge of the arms D. Since the upper ends of the said arms come flush with the upper edge of the wick-tube, the working of the blade over the arms will serve to keep it in a proper position, so that it 100

will sweep over the entire upper edge of the wick-tube, clear the accumulation of matter therefrom, and push it over to the opposite side of the wick-tube.

5 The operation of my invention is as follows: The spring G serves to retain the parts normally in the position shown in Fig. 1, the extension *h* of the blade resting on the diaphragm A' of the burner, while the sharpened front 10 edge of the blade is held at all times against the upper edge of the arms D by the action of the spring G. The inclined arm *b* is also held against the lower edge of the burner by the action of the spring. By pressing against or 15 swinging the end *e* of the rod E the main arm *a* is rotated, causing the winding of the coils of the spring thereon, and also causing the blade F to work over the arms D, and transversely across the upper edge of the wick-tube. By 20 the working of the blade over the upper edge of the wick-tube the light is caused to be extinguished, and the hard crust which always remains on the upper edge of the wick is severed; and as the blade sweeps entirely across 25 and beyond the wick-tube the severed portion of the wick is carried over by the blade to the opposite side of the wick-tube. As soon as the hand of the operator is released from the end 30 *e* of the rod E the spring G reacts and causes the blade F and the rod to be restored to their normal position.

It will be observed that the action of the extinguishing and trimming attachment is decidedly more positive than the spring-pressed 35 cap or cover described and claimed in my aforesaid patent. The trimming of the wick and extinguishing of the flame do not depend upon the uncertainties of a spring action, such as follows from the use of a spring-pressed cap 40 or cover. The movement and operation of the blade are communicated directly from the hand of the operator, the spring employed being used merely to retain the blade in engagement with the arms D, and also to restore the parts 45 to their normal positions after the operation has been completed.

I have shown the blade F as pivoted on the arm *f* of the rod E, and provided with a spring to retain the blade at an incline, with its front 50 edge resting on the arms D. In place of this arrangement I may dispense with the spring, pressed pivotal attachment of the blade and secure it rigidly on the arm *f*, care being taken to have the blade set normally, and at 55 all times on an incline and in engagement with the upper edges of the arms D. Of course when this arrangement is adopted it will not be necessary to employ the curved guide-arms D, and they are therefore dispensed with, and 60 a spring should still be employed to restore the operating-rod E with the blade to a normal position; but the spring should not connect with the blade at all, it acting only on the rod E, which, being fixed with the blade, 65 will cause the latter to follow the movement of the rod. However, I prefer the construction shown, as it enables the parts to be more

readily fitted in position on the lamp-burner. In this manner I provide an attachment which will simultaneously extinguish the 70 light and trim the wick. As the blade travels over the entire upper edge of the wick-tube it will be caused to trim every portion of the wick, and thus unevenness will be avoided, so as to insure a perfect light. By my present 75 improvement I simplify the construction shown in my aforesaid patent, reducing the number of parts necessary to constitute an attachment, changing the mode of operation so as to insure a more positive action, and 80 making such additional improvements as the test of practical use had found it necessary to employ.

It will be observed from the foregoing description, taken in connection with the drawings, that the blade is arranged on one side of the wick-tube of the burner, and that it is normally held depressed below the plane of the upper edge thereof, so that it will not interfere with the light when the lamp is in use, 90 and will not be in the way of the hinged cap of the burner in operating the latter.

Changes in the form and construction of parts may be resorted to without departing from the spirit or scope of my invention.

It will be understood that in the present arrangement I employ the positive action of the hand of the operator to work the blade, and a spring to return the same after the operator has completed the necessary movement. Since the 100 operation of the blade is against the pressure of the spring, it will be observed that sufficient force will be given to the blade to insure a positive cutting action, which will cause the wick to be trimmed more effectually than heretofore.

Having described my invention, I claim—

1. The combination, with a lamp-burner, of a horizontal rock-arm, *a*, carrying the angle-arm *d* and the arm *f*, and having a crank-arm, *b*, the blade F, carried by the arm *f*, and a spring in engagement with the rock-arm for holding the arm *f* and its blade normally depressed below the wick-tube of the burner, substantially as described, for the purpose set 115 forth.

2. The combination, with a burner, of a rock-arm carrying a pivoted blade, guides on which said blade bears, and a spring for normally holding the blade depressed below the 120 wick-tube, substantially as described.

3. The combination, with a burner, of a rock-arm, a blade pivoted on and carried by said arm, curved guides on which the blade bears, and a spring for normally holding the 125 blade depressed below the wick-tube, substantially as described.

4. The combination, with a burner, of a spring-actuated rock-arm having an operating-handle, a spring-actuated blade pivoted 130 on and carried by the rock-arm, and guides on which the blade bears, substantially as described.

5. The combination, with a burner, of a

rock-arm, *a*, having an operating handle and an arm, *f*, curved guides *D*, a blade pivoted on the arm *f* and bearing against the guides, and a spring coiled around the arms *a* *f*, and bearing at its ends against the burner and the blade, substantially as described.

5 6. A lamp trimming and extinguishing attachment, comprising a plate, a rock-arm journaled on the plate and carrying a blade,

and a coiled spring for normally holding the 10 blade depressed, substantially as described.

In testimony that I claim the foregoing as my own I have hereto affixed my signature in presence of two witnesses.

FRANK H. MARKER.
